Letters Patent No. 1075, dated Jan. 4, 1859.

The schedule referred to in these Letters Patent and making part of the same.

To all whom it may concern:

Be it known that we Conrad Harris and Paul Wm. Joiner, both of Cincinnati County of Hamilton State of Ohio, have invented or produced a new and original design for Dining Room Stoves, and we do hereby declare that the following is a full and exact description thereof, reference being had to the accompanying drawings and to the letters of reference marked thereon, in which

Letter A, shows a perspective view of the Stove.

Letter B, the top for Sheet Iron Drum when used for a Cottage Stove.

Letter C, showing a cast Iron Ornament for the front of Sheet Iron Drum.

Having thus fully described our joint invention, what we claim as new and desire to secure by letters ^{patent}, is, the scroll figures and fluting as set forth in the annexed drawings thereby forming an ornamental design for Dining Room Stoves to be called the Ohio.
